UNITED STATES PATENT OFFICE.

AUGUST J. KOEPSELL, OF MAYVILLE, WISCONSIN.

LOOSE-LEAF BINDER.

Application filed November 18, 1922. Serial No. 601,753.

To all whom it may concern:

Be it known that I, AUGUST J. KOEPSELL, a citizen of the United States, residing at Mayville, in the county of Dodge and State 5 of Wisconsin, have invented certain new and useful Improvements in Loose-Leaf Binders, of which the following is a specification, reference being had to the accompanying drawings.

10 This invention relates to binders for loose leaves, and particularly to those binders in which the loose leaves are engaged by rings.

Loose leaf binders are made up in a large variety of styles and the rings are disposed 15 different distances apart and as a consequence the leaves which are punched to suit one binder or one set of rings will not fit notebooks or the like having rings arranged for other punchings. As a consequence, it is 20 necessary to secure paper which is punched in a certain manner for any particular binder and this is sometimes difficult to achieve. Loose leaf notebooks are used in schools to a very large extent to-day and 25 this difficulty in readily securing paper which has been punched to fit any particular type of binder is a vexation.

The object of this invention is to provide 30 a binding device of this character in which the rings for engaging the paper are adjustable toward or from each other so that any paper may be used with any particular binder, thus doing away with the necessity of carrying many different types of cut 35 leaves punched to suit many different styles of binders.

A further object is to provide a device of 40 this character in which the rings are adjustable toward or from each other and in which the rings may be held in their adjusted positions.

A still further object is to provide a binder 45 in which the spaces between the ends of the split rings may be closed by merely turning an operating shaft which will act to close all of the rings or open all of the rings.

Another object is to provide a device of 50 this character which may be adapted to carry any number of rings, which is relatively simple, may be cheaply made, and which will be thoroughly effective in actual practice.

Other objects will appear in the course of the following description.

My invention is illustrated in the accompanying drawings, wherein:—

Figure 1 is a top plan view of my device applied to the cover of a notebook;

Figure 2 is a longitudinal sectional view through the back of the notebook and my 60 mechanism;

Figure 3 is a section on the line 3—3 of Figure 2 with the notebook cover omitted;

Figure 4 is a perspective view of the upper plate;

Figure 5 is a perspective view of the lower plate;

Figure 6 is a section on the line 6—6 of Figure 1;

Figure 7 is a section on the line 7—7 of 70 Figure 1.

Referring to these drawings, 10 designates a base plate which is relatively long and relatively narrow and has apertures at its ends whereby rivets 11 may be used to attach the base plate to the cover 12 of the book. This base plate 10 is provided on opposite edges with the upwardly extending 75 flanges 13. This base plate 10 is made of thin sheet metal.

Resting upon the base plate 10 is a longitudinally extending upper plate 14 which for the greater portion of its length is narrower than the plate 13 but at its middle has a width approximately equal to that of the strip or base plate 10 as at 15, which enlarged portion 15 is formed with the downwardly extending flanges 16 which are adapted to fit inside of the flanges 13. This enlarged portion 15 is formed with a centrally disposed, upstanding screw 17, and on each side of this screw with rectangular apertures 18. The extremities of the plate 14 are also enlarged at 19. This portion at its end is downwardly turned and then longitudinally extended at 20 to form a foot riveted to the strip 10 by the rivets 11. The portions 19 are closed at their sides by flanges 21 and the downwardly extending wall 22 is apertured at 23 to form a bearing. 100

Disposed to rest upon the base plate 10 are a plurality of slides 24, each slide 24 having a width approximately equal to the distance between the flanges 16 and being guided by these flanges and having a longitudinally extending shank 25 which is offset with relation to the center line of the corresponding slide 24. Certain of these slides 105

24 have their shanks 25 disposed adjacent one of the flanges 16 and the shanks of the other slides 24 are disposed against the other flange 16 so that the shanks of one series of 5 slides overlap the shanks of the other series of slides. These slides carry upon them tubular ring portions 26 which are attached to the slides by soldering, riveting or otherwise. These rings extend out around 10 the upper plate 14. The slides are held in their adjusted positions by means of a binding plate 27 which rests upon the upper face of the portion 15 of plate 14 and which has downward projections 28 which pass 15 through the apertures 18 and which rest upon the shanks 25. This plate 27 is apertured at its center to receive the upstanding screw 17 and a nut 29 engages this screw-threaded post or bolt and, of course, bears 20 upon the binding plate 27. Thus as the nut is turned down, the projections 28 will bear against the shanks 25 and lock these shanks against longitudinal shifting movement between the flanges 13 and with relation to 25 each other. When the set nut 29 is turned off, however, it is obvious that these slides 24 may be shifted by hand to any desired position and then again locked.

30 Each of the tubular rings 26 has a gap in its upper portion and disposed within each tubular ring is a slidable section 30, arcuate in form, housed within the ring and adapted, when shifted in one direction, to close the gap between the ends of the ring and 35 form a continuation thereof and, when shifted in the other direction, to open this gap. This permits the insertion of the paper in the ring, and the closing of the ring through the perforation in the paper.

40 For the purpose of operating all of these members 30 simultaneously, I mount in the apertures 23 the operating shaft 31, this shaft having reduced portions 32 which fit in the bearings 23. Between these reduced 45 portions the shaft is provided with a longitudinally extended cylindrical toothed gear 33. The inner faces of the rings 26 are cut away at 34 and this toothed portion 33 fits in this cut-away portion 34 and engages 50 with teeth 35 formed upon each member 30. Therefore, it is obvious that as the shaft 31 is rotated in one direction the members 30 will be projected to close the gap in all of the rings and upon the rotation of the shaft 55 31 in the opposite direction the members 30 will be retracted to open the gap in the rings. This member 31 has a shank 36 provided with a head whereby the shaft may be rotated. Preferably this head 37 is pivoted at 38 to the shaft so that the head may be turned into a position at right angles to the shaft or into alignment with the shaft. This head or handle is to be thrown back 60 into angular relation to the shaft when not in use. The elongated teeth 33 will obvi-

ously permit the rings to be shifted longitudinally without getting out of mesh with this elongated gear.

While this loose leaf binder might be formed with only two rings 30, it is obvious 70 that any number of rings may be used. In this case the slides will rest one on top of the other, as illustrated in Figure 2. The shanks on each side of the device will rest one on top of the other so that all of the shanks as, for instance, three shanks if there are three slides on each end of the device, will come beneath and be bound by the projections 28 of the binding plate 27. By taking hold of any particular ring, however, it is obvious that that particular slide, provided the nut 29 has been turned off, may be shifted to any desired position. Then when the nut is turned down, it is obvious 80 that the projections 28 will bind on all three of the shanks, or as many shanks as there may be on one side of the device, and hold all of the rings on that side from longitudinal movement. Then after the rings have been adjusted longitudinally so as to bring 85 these rings to the proper position to engage the holes punched in the note paper, the shaft may be rotated to project all of the members 30 of the several rings so that these members will be forced through the holes in 90 the paper and the leaves will be bound by the rings. Of course, when the handle 37 is turned into angular relation it bears against the cover of the back and the shaft 95 31 cannot be further turned until the handle 100 is drawn out into alignment with the shaft. It will be seen that the adjustability of the rings on my device does away with the necessity of a stationer carrying many different kinds of paper just for the purpose of 105 being able to supply the demand for paper suited to many different kinds of covers. The device may be very simply and cheaply made and at the same time may be thoroughly substantial. Obviously many 110 changes might be made in the details of construction and arrangement of parts without departing from the spirit of the invention as defined in the appended claims.

I claim:—

1. In a loose leaf binder, a base, a plurality of slides mounted upon the base for longitudinal movement, each slide carrying a ring, each slide having a shank, and means for engaging all of said shanks for holding the rings in adjusted position.

2. In a loose leaf binder, a base, slides mounted on each side of the middle of the base, each slide being longitudinally adjustable, the several slides having longitudinally extending shanks, the shanks on each side of the base extending toward the middle of the base and overlapping the shanks of the slides on the other side of the base, and means at the middle of the base for engag-

- ing both sets of shanks for locking the slides in their adjusted position.
3. In a loose leaf binder, a base, slides mounted on each side of the middle of the base, each slide being longitudinally adjustable, the several slides having longitudinally extending shanks, the shanks on each side of the base extending toward the middle of the base and overlapping the shanks of the 10 slides on the other side of the base, means at the middle of the base for engaging both sets of shanks for locking the slides in their adjusted position, said means comprising a binding plate having downward projections, a bolt passing through the binding plate, and a nut on the bolt engaging the binding plate.
4. A loose leaf binder of the character described comprising a base plate, an upper plate mounted upon the base plate and having an upwardly extending screw-threaded post at its middle, a plurality of slides mounted upon the base plate on each side of the middle of the plate, each slide carrying rings extending downward between the top 20 plate and the base plate and each slide having shanks extending to and beyond the middle of the base plate, the top plate having lateral apertures disposed above said shanks, a binding plate mounted upon the cover plate and having downward projections extending through said apertures and bearing upon the shanks of the slides, and a nut engaging said post and adapted to engage the binding plate.
5. In a loose leaf binder, a base, a series of tubular split rings mounted on the base, a member disposed within each ring and movable circumferentially therein and when projected closing the gap in said ring and 30 when retracted opening the gap in said ring, and common means for shifting all of said members simultaneously in one direction or the other including a longitudinally extending shaft having gear teeth cut therein and adapted to engage and mesh with the teeth on said members, said shaft at one end having a handle pivoted to the shaft for movement into axial alignment therewith to thereby permit the rotation of the same but 40 adapted to be turned at right angles thereto and into locking engagement with the base to lock the shaft from rotation.
6. In a loose leaf binder, two series of rings disposed on opposite sides of the middle of the binder, each ring being adjustable toward or from the middle of the binder, each ring being tubular and split and open at one point, a circumferentially movable member disposed within each ring and 50 adapted to be projected or retracted to close or disclose the opening therein, means for locking the rings in longitudinally shifted positions with relation to each other, and common means for all of said ring portions for projecting or retracting said members.
7. In a loose leaf binder, a base plate, a top plate carried upon but spaced from the base plate, a plurality of slides mounted upon the base plate and movable toward or from each other and the middle of the base plate, each slide having a shank extending beyond the middle of the base plate, means on the top plate for locking said slides in adjusted position, a longitudinally extending shaft operatively mounted between the base plate and top plate and having longitudinally extending gear teeth, a series of tubular ring portions each mounted upon one of said slides and extending in a plane at right angles to the shaft and having a gap on its inner face through which the teeth of the shaft project and having a gap at its upper portion, a member disposed within each ring portion and projectible to close the gap in the ring or retractible into the ring, each member having gear teeth engageable by the gear teeth on the shaft, means for rotating the shaft, and means for locking the shaft in rotated position.
8. In a loose leaf binder, a base plate, a top plate carried upon but spaced from the base plate, a plurality of slides mounted upon the base plate and movable toward or from each other and the middle of the base plate, each slide having a shank extending beyond the middle of the base plate, means on the top plate for locking said slides in adjusted position, a longitudinally extending shaft operatively mounted between the base plate and top plate and having longitudinally extending gear teeth, a series of tubular ring portions each mounted upon one of said slides and extending in a plane at right angles to the shaft and having an opening on its inner face through which the teeth of the shaft project and having a gap in its upper portion, a member disposed within each ring portion and projectible to close the gap in the ring or retractible into the ring, each member having gear teeth engageable by the gear teeth on the shaft, and means for operating the shaft comprising a handle adapted to be disposed in axial alignment with the shaft to thereby rotate the same but pivoted to the shaft to be turned at right angles thereto to thereby lock the shaft from rotation.

In testimony whereof I hereunto affix my signature.

AUGUST J. KOEPSELL.
